UNITED STATES PATENT OFFICE.

ADALBERT BESTA, OF DUISBURG, GERMANY.

APPARATUS FOR CARBONIZING BITUMINOUS FUELS.

Application filed December 27, 1924, Serial No. 758,372.

To all whom it may concern:

Be it known that I, ADALBERT BESTA, a citizen of the German Republic, and a resident of Duisburg, Germany, have invented certain new and useful Improvements in Apparatus for Carbonizing Bituminous Fuels (for which I have filed application in Germany, December 24, 1923), of which the following is a specification.

10 The methods of, and the means for, carbonizing bituminous fuels as employed hitherto aimed either at passing as much material as possible through the fire in a certain period of time, or at producing a dust-free gas.

15 The object of the present invention is to do both within a comparatively small apparatus. The fuels are gasified in this apparatus with the aid of horizontally or vertically disposed circular cell-systems having 20 on all sides heated surfaces.

The fuel is supplied automatically by causing it to slide down from a receptacle located on a higher level than the cell to be filled.

25 The cells are emptied all at the same place which is located laterally from that place where the cells are filled; at the other side of this place the fuel introduced into the cells is compressed.

30 If the circular cell-system is arranged vertically its cells may be closed on both sides or on only one side. In the first of these cases the heating means may be provided in exteriorly disposed mantles, the arrangement being then such that the heating gases wash the cell-walls exteriorly, as well as interiorly, and are conducted off upwardly from the centre of the circular cell system.

35 The heating can be effected, however, also 40 in such a way that the middle portion of the circular system of cells is heated and the heating gases are then conducted away outwardly.

The arrangement may, furthermore, be 45 such that the heating can be effected alternately in the direction from the periphery to the centre and from this to the periphery so that the cell-walls are heated very uniformly.

50 In order to conduct the heating gases uniformly along the cell-walls in the case of exterior heating, the outlet-tube extends upwardly and is provided with outlet-openings which decrease in the upward direction of 55 this tube.

The exteriorly disposed heating chamber

may be subdivided into several chambers or compartments by means of inserted partition walls which extend radially with respect to the circular cell-system so that the cells 60 which pass, while the cell-system is turning, in front of said walls are heated to different temperatures in their various positions.

The heating may be regulated by means of turnable burner-tubes arranged in front 65 of the burner-openings, and being each provided with slots, as well as with a tube that can be turned upon the burner-tube to which it appertains and the operative end of which is smooth on one side and toothed like saw-teeth on its other side. The amount of gas to be supplied by a burner-tube of this kind is regulated by turning the outer tube more or less. The amount of air can be regulated by adjusting the burner-tubes relatively to 70 the burner openings.

The retort may be heated also by burners of another kind, provided, the cells can be heated uniformly by means of them.

The stationary bottom-plate may be heated 80 either partly or around its entire circumference.

The degasified coke is discharged downwardly at a certain position of the cells. The bottom-plate is provided with an aperture 85 through which the coke falls into a collecting space from which it can be discharged either through a water-seal or by means of a cell-wheel.

In the position following the discharge 90 of the coke the emptied cell is filled with another charge of fuel to be gasified, the filling being effected by causing the material to slide down from a drying-shaft located above the circular cell-system. Owing to the 95 rotation of the circular cell system the filled cell travels to and into the next position where the material is compressed by a suitably disposed compressing device so that it is transformed into a solid cake and can 100 expand upwardly while the degasification proceeds, without rising over the upper cell- 105 rim.

The carbonizing-gas device located above the cells can be divided into several compartments so that said gases for instance in the case of moderate heating or of heating with medium intensity or in the case of intense heating can be conducted away separately.

The rotatory cell-system is sealed relative to the stationary part of the retort by 110

means of gutters filled with tar so that the spaces containing by-product gas are securely separated from the atmosphere. The tar contained in said gutters is cooled by tubes immersed in it and containing flowing water; there are two such gutters above the cell-system and one below it, all gutters being enclosed in the stationary outer casing. Owing to this part being stationary, as just stated, the supply and the discharge of the cooling water can be effected without any difficulty. Instead of arranging cooling pipes proper in the said gutter, or in the tar respectively, each gutter may have a double bottom, the cooling water being then caused to flow in the channel formed by said two bottoms and the appertaining parts of the lateral walls.

The movable parts of the retort are supported by a vertical pivot which is the chief supporting means, and besides said pivot a circle of rolls is provided which hold the cell system in proper position vertically and horizontally.

Prior to conducting the carbonizing material to the cells, it may be pre-heated and pre-dried in a shaft. A part of the heating gases escaping from the cells can be branched off and used for effecting said preliminary heating and drying.

The retort may be built also in such a way that the exterior part is rotating and the cell-system is stationary.

In lieu of a sliding plate located below the cells, flaps, or equivalent members may be provided which are opened automatically at the place where the material treated shall leave the cell-system, this material being, by the means provided in lieu of said plate, prevented from sliding on such a plate.

With the vertically disposed circular cell-systems having cells that are open on one side the material travels on the open side of the cells along a heating plate so that it is heated on all sides also with systems of this kind. According as the open side of the cells is directed outwardly or inwardly, the heating plate closing the cells on that side may also be arranged outwardly or inwardly. The heating gases may be conducted also with these systems from the centre to the periphery, or reversely, or the two directions may alternate with one another.

Additional burners may be provided in order to render the heating more uniform.

The seal between the rotatory and the stationary part of the retort may be effected also in this case by gutters containing tar, but it is also possible to provide stuffing-boxes for that purpose.

Also the retorts with vertical cells may be so devised that the exterior parts are rotatory, whereas the cell-system proper is stationary.

With the retorts with horizontally dis-

posed cell-system the cells are open on their outer side, and are emptied wholly or partly at a certain position of the system. The filled cells which have been filled at a place lying near that where the emptying takes place pass along a heating plate so that the material is again heated on all sides. Also with these systems the heating gases may be conducted radially inwards or outwards, or alternately in both directions, and additional burners may be provided to render the heating still more uniform.

The heat is transmitted quickly also to the inner parts of the individual charges of the material introduced into the cells as it is heated from all sides at a time, whereby the time of heating it thoroughly is shortened materially.

My invention is illustrated diagrammatically and by way of example in the accompanying drawing in which Figure 1 is a vertical axial section through one constructional form of a retort devised for carrying the method into practice; Figure 1a is an enlarged view of a section of one of the adjustable burners, Figure 2 is a horizontal section in the plane II-II of Fig. 1; Figure 3 is an illustration similar to Fig. 1, showing a modification; Figure 4 is a horizontal section in the plane IV-IV of Fig. 3; Figure 5 is a vertical axial section through another modification, the axis of this retort lying horizontally instead of standing vertically; and Figure 6 is a vertical section in the plane VI-VI of Fig. 5.

Referring to Figs. 1 and 2, the cells of this constructional form of the retort are laterally completely closed; the retort is heated exteriorly and the heating gases escape centrally in upward direction. *a* denotes the circular cell-system which is carried centrally by the pivot *b* and is rotated by the worm-gearing *c*. The cell-wheel is supported also by circularly disposed rolls *d*, the chief object of which is to maintain the said system in proper position horizontally and vertically.

The cell-system *a* is surrounded with a cylindrical wall *e* which is, preferably, lined with a refractory material and is called "heating mantle" in the following part of this specification. The heating mantle *e* is provided with vertical slots *f* termed "burner-openings" in the following part of this specification. In front of these openings oscillable burner-tubes *g* are arranged which are supplied with heating gas by annular pipes *h¹* *h²*.

The burner-tubes *g* are each composed of an inner tube *i* having vertical slots *k*, and of an outer tube *l* having vertical slots *m*, the vertical rims or edges of which are actually vertical on one side of the slot and shaped like saw-teeth on the opposite side. The slots *k* can, therefore, be closed

more or less, as required, by turning more or less the appertaining tube l , and besides, owing to the spaces between the teeth on one side of each slot m the heating gas passing through said spaces acts similarly to a spray.

Also the air-supply can be regulated owing to the tubes i being turnable in the nipples, by which they are branched off from the annular fuel feeding tubes h^1 and h^2 . By this oscillating or swinging movement of the burner tubes g their orifice slots k are moved towards or away from the slots f in the cylindrical wall or heating mantle e , which lateral adjustment results in a corresponding change of the injector-like suction of air into the carbonizing chamber.

n denotes throttling valves inserted between the bent upper and lower ends of the burner-tubes g and the supply pipe h^1 , h^2 .

Outside the circular cell-system a some inwardly projecting radial partition-wall o are provided by which the heating space enclosing the cells is divided into several compartments whereby it is rendered possible to heat the cells to different temperatures in the different positions they assume while the circular cell-system is being rotated.

In the constructional form shown by way of example in Figs. 1 and 2 there are three partition-walls and, consequently, three compartments, of which one is intended for moderate heating, the other for heating of medium intensity, and the third for strong heating.

The heating gases pass through the retort in the directions indicated by the arrows and are conducted away, finally, through the central tube p from which they escape at the upper end. This tube is provided with vertical slots q which form superposed series and in which the slots of an upper series are lower or shorter than the slots in the series therebelow, so that the gases are distributed practically uniformly over all cells.

Laterally from the uppermost part of the discharge-tube p a pre-drying device for the coal is arranged, and within said part of the tube p a throttling valve r is provided, and a passage is established between the said tube-part and said pre-drying device, the arrangement being such that a part of the escaping gases can be caused to pass through the mantle of said pre-heating device in order to contribute to the drying of the coal therein contained.

In the position I the coked material is discharged; in the position II fresh coal is supplied from the coal-shaft t , and in the position III the material to be carbonized is compressed by means of a compression device u .

v denotes the annular collector for the by-product gas distilled from the fuel, said collector being separated from the outer air

by two annular concentric gutters w filled with tar; a third gutter w^1 filled with tar is provided below the cell-system, and an annular sheet metal member dips into the tar contained in this gutter so that the by-product gases present below the cell-system cannot escape into the atmosphere. Within the upper gutters w cooling-pipes x^1 and x^2 are provided, and a third cooling pipe x^3 is provided in the lower gutter w^1 , the object of these pipes through which water is flowing being to cool the tar contained in the said gutters.

The by-product gases are led away from the gas collector v through the pipe y . The bottom-plate z is heated by burners z^1 arranged below it.

The cell-system is rotated in the direction indicated by the arrow shown in Fig. 2.

The retort illustrated in Figs. 3 and 4 has outwardly open cells. The cells pass along the heating mantle e^1 which is heated by the burners 2 . The heating gases flow in the direction of the arrows through the tube 3 into the inner part of the heating system and escape through the tube 4 . Within the heating system a cylindrical guide-plate 5 is provided by which the gases are caused to pass along the walls of the cells. The retort is sealed at its upper part by a tar-containing gutter w^3 and at its lower part by a stuffing-box 6 . Filling the cells, compressing the material filled into them, and emptying the cells, is effected practically in the same manner as has been described with respect to the constructional form shown in Figs. 1 and 2. 7 , at the lower part of the retort, denotes an additional burner. The circular cell-system is rotated in the direction indicated by the arrow.

The retort shown in Figs. 5 and 6 is provided with a horizontal cell-system. The cells are outwardly open and pass along the heating mantle e^2 which is heated by burners 9 . The heating gases wash the mantle e^2 in the direction indicated by the arrow, are then conducted by the tubes 10 radially inwards, wash the cell-walls within the drum, and escape through the tube 11 . Centrally within the circular cell-system is a cylindrical guide-plate 12 . On the side lying opposite the tube 11 an additional burner 13 is provided. When the cells are in the position denoted I the coke is discharged wholly or partially from the cells; in the position II the cells are being filled, in that the carbonizing material slides down by itself thereinto. The by-product gases are conducted off the receiver 16 by the tube 17 . The cell-system is driven by a worm-gear 18 , supported on rolls 19 , and rotated in the direction indicated by the arrow.

I claim:

1. An apparatus for carbonizing bitumi-

130

1. A apparatus for carbonizing bituminous fuels, comprising, in combination, a plurality of cells spaced apart and fixedly grouped into an annular series; means for rotating the cells; means for heating the cells on all sides; means for feeding the cells with the respective fuel one after the other at one definite place; means for compressing the fuel in the filled cell at a neighbouring place, and means for discharging the degasified fuel again at a neighbouring place, substantially as described. 70
2. An apparatus for carbonizing bituminous fuels, comprising, in combination, a plurality of cells spaced apart and fixedly grouped into an annular series and adapted to be turned around a vertical axis; means for closing the cells laterally; means for rotating the cells; means for conducting heating gases around the cells radially inwards, causing them to wash the cell-walls at all sides; and a centrally disposed gas-outlet tube having outlet apertures increasing in their free sectional area in downward direction, substantially as described. 80
3. An apparatus for carbonizing bituminous fuels, comprising, in combination, a plurality of cells spaced apart and fixedly grouped into an annular series and adapted to be turned around a vertical axis; means for closing the cells laterally; means for rotating the cells; means for conducting heating gases around the cells radially inwards, causing them to wash the cell-walls at all sides; a stationary mantle enclosing the said system of cells; and adjustable burners provided at said mantle, substantially as described. 90
4. An apparatus for carbonizing bituminous fuels, comprising, in combination, a plurality of cells spaced apart and fixedly grouped into an annular series and adapted to be turned around a vertical axis; means for heating the cells on all sides with the exception of the upper side; a stationary mantle enclosing the cells; adjustable burners provided at said mantle, and heating-gas supplying tubes attached to the mantle and having said burners attached to them, substantially as described. 100
5. An apparatus for carbonizing bituminous fuels, comprising, in combination, a plurality of cells spaced apart and fixedly grouped into an annular series and adapted to be turned around a vertical axis; means for heating the cells on all sides with the exception of the upper side; a stationary mantle enclosing the cells; telescopically arranged heating-gas supplying tubes having slots, the inner tubes being stationary and the outer ones being rotatable and their slots having saw-shaped teeth at one side, substantially as described. 110
6. An apparatus for carbonizing bituminous fuels, comprising, in combination, a plurality of cells spaced apart and fixedly grouped into an annular series and adapted to be turned around a vertical axis; means for heating the cells on all sides with the exception of the upper side; a stationary mantle enclosing the cells, circular liquid seals arranged above and below the retort, the said liquid seals consisting of circular tar filled gutters cooperating with circular partitions dipping from above into the tar filling of the gutters, and the said liquid seals being adapted to separate, with the aid of the tar, the interior of the cell-system from the atmosphere, substantially as described. 120
7. An apparatus for carbonizing bituminous fuels, comprising, in combination, a plurality of cells spaced apart and fixedly grouped into an annular series and adapted to be turned around a vertical axis; means for heating the cells on all sides with the exception of the upper side; a stationary mantle enclosing the cells, circular liquid seals arranged above and below the retort, the said liquid seals consisting of circular tar filled gutters cooperating with circular partitions dipping from above into the tar filling of the gutters, and the said liquid seals being adapted to separate, with the aid of the tar, the interior of the cell-system from the atmosphere, and cooling pipes arranged within the tar, substantially as described. 130
8. An apparatus for carbonizing bituminous fuels, comprising, in combination, a plurality of cells spaced apart and fixedly grouped into an annular series and adapted to be turned around a vertical axis; means for heating the cells on all sides with the exception of the upper side; a stationary mantle enclosing the cells, concentric circular liquid seals provided above the retort, consisting of concentric tar filled circular gutters arranged above the rotatory part of the retort and cooperating with circular partitions attached to the stationary part of the apparatus above the rotary retort and dipping into the tar filling of said gutters; another circular liquid seal arranged below the retort, consisting of tar filled circular gutter arranged on the ground below the rotatory part of the retort and cooperating with a circular partition attached to the lower side of the rotatory part of the retort and dipping into the tar filling of the last mentioned gutter; all the said liquid seals being adapted to separate, with the aid of the tar, the interior of the cell-system from the atmosphere, substantially as described. 140
9. An apparatus for carbonizing bituminous fuels, comprising, in combination, a plurality of cells, spaced apart and fixedly grouped into an annular series and adapted to be turned around a vertical axis; means for rotating the cell-system; a stationary bottom plate arranged below the cell-system. 150

- and means for heating the cells on all sides with the exception of the upper side, and for heating also at least parts of said bottom plate, substantially as described.
- 5 10. An apparatus for carbonizing bituminous fuels, comprising, in combination, a plurality of cells spaced apart and fixedly grouped into an annular series and adapted to be turned around a vertical axis; means for heating the cells on all sides with the exception of the upper side; a stationary mantle enclosing the cells; circular liquid seals arranged above and below the retort, the said liquid seals consisting of circular tar filled gutters cooperating with circular partitions dipping from above into the tar filling of the gutters, and the said liquid seals being adapted to separate, with the aid of the tar, the interior of the cell-system from the atmosphere, a circular stationary collector for the by-product gas connected with said circular partitions, and at least one outlet-pipe for the by-product gases, substantially as described.
11. An apparatus for carbonizing bituminous fuels, comprising, in combination, a plurality of cells spaced apart and fixedly grouped into an annular series; means for rotating the cells; means for heating the cells on all sides with the exception of the upper side; means for feeding the cells with the respective fuel one after the other at one definite place; means for compressing the fuel in the filled cell at a neighbouring place, and means for discharging the degasified fuel again at a neighbouring place, means for supplying heating gases of several temperatures so as to heat the cells correspondingly to different temperatures, substantially as described.

In testimony whereof I affix my signature.

ADALBERT BESTA.
